UNITED STATES PATENT OFFICE.

FREDERICK S. GUERBER, OF WHITE PLAINS, NEW YORK.

INVALID-CHAIR.

1,286,295.

Specification of Letters Patent.

Patented Dec. 3, 1918.

Application filed June 29, 1914. Serial No. 847,862.

To all whom it may concern:

Be it known that I, FREDERICK S. GUERBER, a citizen of the United States, residing at White Plains, county of Westchester, State 5 of New York, have invented certain new and useful Improvements in Invalid-Chairs, of which the following is a clear, full, and exact description.

The object of the invention is to provide 10 an invalid chair which shall be economical to make, easy to push about, comfortable for the occupant, of light and strong construction, and which shall be adjustable in height yet firmly supported as to both vertical 15 load and horizontal sway and protected against overturning. The chair has a unit under-frame of special form, to which are secured a main axle for a pair of carrying wheels disposed below and well forward of 20 the chair back, a pilot wheel, and a pair of runners, and between which and the chair body are vertically adjustable connections located at the axle, over the pilot wheel and at the forward ends of the runners, respectively.

In the drawings:

Figure 1 is a sectional view of an invalid chair embodying my improvement.

Fig. 2 is a plan view, the section being 30 taken on line 2—2 in Fig. 1.

Fig. 3 is an enlarged front view, the upper part of the chair being broken away.

Fig. 4 is an enlarged sectional plan view of the horizontal frame, the section being 35 taken on a line 4—4 in Fig. 1, some of the members being omitted.

Fig. 5 is an enlarged sectional plan view of a portion of the horizontal frame and connected runner.

As herein illustrated, my improved chair 40 consists of a body A, consisting of a seat 1, sides 2 and a tilttable back 3. To produce a cheap body, I secure the sides 2 to the seat 1 by straps 4, Fig. 2, which in turn are secured to the seat 1. The seat 1 is supported by a substantially flat horizontal unit under-frame 5, Fig. 4, consisting of axle hubs 6, a pilot wheel axle hub 7, arms or ribs 8 converging from the axle hub to the pilot wheel, 45 axle hub and arms or ribs 9 diverging from the ribs 8. The outer end of each arm 9 carries a tubular hub 10 to receive the upturned member 11 of a runner or guard 12. The rear member 13 of each guard 12 is secured to a bracket 14 on each axle hub 6.

Each bracket 14 has also secured thereto a brace 15 which supports the body of the chair by being secured to the seat 1 by screws 16. To the outer end of each brace 15 I secure a clamp 17, which rotatably supports 60 the back 3 of the body of the chair.

To brace the back 3 of the body I employ braces 18 secured at one end to the bottom 1 of the chair, the opposite end passing through the back and provided with threads 65 to receive a tubular nut 19. To alter the inclination of the back 3 the nuts 19 will be backed off, presuming that the back is at its highest point of inclination in Fig. 1, which will permit the back to be swung upon 70 its pivotal connection at the brackets 17 and inclined rearwardly the desired amount. When the nuts 19 are removed the back 3 can be moved to a position in line with the seat 1, or horizontal. The front of the body 75 A is provided with tubular posts 20 secured to the seat 1 at 20°, which are fitted into the tubular member 11 of the guards 12, and which are adapted for vertical movement or adjustment therein. Each guard member 11 80 is provided with a plurality of openings or passages 21, adapted to receive a pin 22, which also passes through an opening, not shown, in the posts 20. The front of the chair can be raised or lowered by altering 85 the position of the posts 20 in the guard members 11. The posts 20 are preferably located somewhat forward of the chair seat, and their upper portions 47 are bent rearward and inward and their ends secured beneath the seat. Each brace 15 is also provided with openings 23, Fig. 3; to adjust the height of the chair the bolts 24 will be removed and the braces 15 adjusted on the brackets 14. To facilitate the rolling of the 90 chair forward, rearward, or when turning, I provide the hub 7, of the horizontal frame 5 with a rotatable carriage 25 carrying a yoke 26 for a pilot wheel 27. The carriage 25 is tubular and a post 28 passes through 100 the same. The post 28 enters a socket 29 in the seat 1 and is provided with a plurality of openings 30 through any one of which a pin 31 can pass. The weight of the person in the chair is imposed upon the post 28, thence to the pin 31, hub 7, and finally wheel 27. The height of the chair at the front can be altered by adjusting the post 28 in the hub 7. The removable pin 31 permits 105 the adjustment of the said post.

The chair is preferably provided with a foot rest 32, which at its inner end is provided with cleats 33, which rest upon the guards 12 (see Fig. 4). The foot rest is held in an inclined position by open link chains 34, one end of each chain being attached to an eye 35 in the foot rest; the opposite end of the chain engaging a hook 36 in the chair seat 1. To increase the degree of inclination of the foot rest the chain is taken up by causing an intermediate link to engage the hook 36. The foot rest can be entirely removed from the chair by disengaging the chains from the hooks 36 and pulling the foot rest outwardly.

The chair is also preferably provided with a table 37 pivotally supported to posts 38, and adjustable braces 39. The posts 38 consist, in this instance, of two telescoping members 42 and 43^a adjustably secured together by pins 44, which pass through one of a number of openings 45 in the post members 42 and through an alining opening, not shown, in the post member 43^a. The lower end of each member 43^a of the table posts 38 carries a pin 49, Fig. 1, which passes through openings 50 in the frame arms 9.

The chair is provided with an axle 56 carrying wheels 57, the same being located well forward of the back of the chair body, so as to be approximately beneath the center of gravity.

I claim as my invention:

1. An invalid chair comprising, in combination, a chair body, a unit under-frame having a main axle bearing for a pair of carrying wheels below and forward of the back of the chair, a pilot wheel and runners also secured to said unit under-frame, a pair of rear supports for the chair body having vertically adjustable connection with the under-frame adjacent the main axle bearing, another vertically adjustable support over the pilot wheel, and a pair of side supports, also vertically adjustable, between the chair body and the forward corner portions of the under-structure.

2. An invalid chair comprising, in combination, a chair body, an under-frame carrying the same and comprising an axle housing below and well forward of the back of the chair body and frame members extending forward from said axle housing and

having vertical sockets, a pair of main wheels on an axle in said axle housing, a 55 pilot wheel mounted on a central one of said sockets, and runners projecting rearward of the main wheels and having upturned forward portions received in forward corner sockets. 60

3. An invalid chair comprising a chair body, an under-frame having axle hubs located below and well forward of the back of the chair body, and comprising converging arms extending thence forward and 65 bearing a vertical hub or socket, and diverging arms extending forward from the converging arms and bearing forward corner hubs or vertical sockets, in combination with a pilot wheel, runners having rearward extensions, and forward chair body supports, which are connected with said sockets. 70

4. In combination with a chair body, a supporting frame, said frame consisting of a plurality of arms, the free end of each of 75 said arms being provided with a hub, two of said hubs being adapted to receive an axle, the other of said hubs being adapted to receive a supporting element for the chair body. 80

5. In combination with a chair body, a supporting frame, said frame consisting of a plurality of arms, the free end of each of said arms being provided with a hub, two of said hubs being adapted to receive an 85 axle, the other of said hubs being adapted to receive a supporting element for the chair body, and means carried by the frame adapted to support a pilot wheel. 90

6. In combination with a chair body, a supporting frame, wheels carried by said frame, adjustable posts secured to said chair and engaging said frame, a hollow trunnion rotatably supported by said frame, a pivot wheel carried by said trunnion, and an adjustable post passing through said trunnion, and at the upper end thereof, engaging the seat of said chair body. 95

Signed at New York city, New York, this 15th day of June, one thousand nine 100 hundred and fourteen.

FREDERICK S. GUERBER.
